CLAIM

The ornamental design for a bed, as shown and described.

DESCRIPTION

FIG. 1 is a perspective view of a bed showing my new design;

FIG. 2 is a front elevational view thereof;

FIG. 3 is a rear elevational view thereof; and,

FIG. 4 is a side view thereof, the opposite side being a mirror image of the side shown.

The rear of the footboard is substantially identical to the front shown.
